CLAIM

The ornamental design for a wall gasket support structure, as shown and described.

DESCRIPTION

FIG. 1 is an end view of a wall gasket support structure showing my new design.

FIG. 2 is a front view of my new design.

FIG. 3 is a side view of my new design.

FIG. 4 is an end view of an alternative embodiment of my new design.

FIG. 5 is an end view of an alternative embodiment of the present invention.

FIG. 1

FIG. 2

FIG. 3

FIG. 4

FIG. 5
